ROLL TRUING MECHANISM FOR WOOD
PLANERS

Edward Dechau, Wrens, Ga.

Application April 20, 1945, Serial No. 589,397

1 Claim. (Cl. 142—42)

1

My invention relates to improvements in mechanism for truing up rolls of wood planers, the primary object in view being to provide a simply constructed mechanism adapted to be interposed between a pair of rolls of a planing machine and embodying means constructed and arranged to be fed along said rolls while the rolls are rotating to accurately true the same simultaneously and progressively with a minimum of time and labor.

Other and subordinate objects, also comprehended by my invention, together with the precise nature of my improvements, will be readily understood when the succeeding description and claim are read with reference to the drawings accompanying and forming part of this specification.

In said drawings:

Figure 1 is a view in perspective illustrating my improved mechanism applied,

Figure 2 is a view in front elevation,

Figure 3 is a view in transverse section taken on the line 3—3 of Figure 1.

Referring to the drawings by numerals, my invention has been shown therein as applied to a pair of upper and lower rolls 1, 1' of a wood planer and which are provided with the usual reduced end journals 2 by means of which the rolls are rotatably and removably mounted in the planer to be driven, all in a manner well understood in the art and therefore not deemed necessary to illustrate or further describe.

According to my invention, a frame 3 is provided embodying a pair of flat, end cross-bars 4 connected together by a longitudinal, central front track bar 5 secured to said end bars 4 by lateral end flanges 6 on the track bar 5 and bolts 7. The track bar 5 is provided at its front with laterally extending side edge tracks 8 preferably V-shape in cross-section and also with a longitudinal, concave front groove 9 between said tracks 8. The end cross-bars 4 are provided with coplanar, flat, enlarged yokes 10 forming forwardly offset end extensions of said bars 4 and provided with V-notches 11 in the outermost edges thereof, whereby said yokes 10 are adapted to straddle the journals 2 at opposite ends of the rolls 1, 1' and to lie against the ends of said rolls so that the track bar 5 is interposed and centered between the rolls 1, 1' of said pair with its front in the plane of said rolls 1, 1', substantially.

Slidably mounted on the tracks 8 is a rectangular tool carriage 12 having a rear, convex, center guide rib 13 slidably fitted in the groove 9, and a pair of guideways 14 upon opposite sides of said rib 13 slidably fitting over the tracks 8 and conforming in shape therewith.

A pair of bar-type, cutting tools 15, similar to the usual lathe bits, are mounted on the front face of said carriage 12 to extend laterally and vertically oppositely from said carriage into work-

ing engagement with the pair of rolls 1, 1' in substantially radial positions relative to said rolls. Clamping blocks 16 bolted to said carriage, as at 17, secure said tools 15 in place for adjustment toward or from said rolls 1.

A screw shaft 18, with a hand wheel 19 on one end thereof, is rotatably mounted in a bearing bracket 20 on one end of the track bar 5 against endwise movement and threaded through the guide rib 13 of the tool carriage 12, said shaft being accommodated in the groove 9.

Preferably, the tools 15 are staggered, relatively to dispose the same upon opposite sides of the transverse center of the tool carriage 12 to distribute the stresses and strains to the cutting throughout the carriage 12. As will be seen in Figure 3, the track bar 5 extends beyond the end cross-bars 4, and the yokes 10 are provided with spacing bosses 21 between the same and the ends of the rolls 1, 1' so that the tools 15 may cut from end to end of said rolls 1.

The operation of my invention will be readily understood. While the rolls 1, 1' are rotating, the hand wheel 19 is operated to rotate shaft 18 and slide the tool carriage 12 back and forth along said tracks 8 to correspondingly move the tools 15, thereby truing the rolls 1 simultaneously. It may be explained that the invention is designed to be used in connection with wood planers in which the rolls 1, 1' are driven and the upper roll 1 of the pair is vertically adjustable against spring tension and whereby the yokes 10 may be positioned relative to the journals 2 as described while the rolls are mounted in the planer.

The foregoing will, it is believed, suffice to impart a clear understanding of my invention without further explanation.

Manifestly, the invention, as described, is susceptible to modification both as regards structure and combination of parts, without departing from the inventive concept, and right is herein reserved to such modifications as fall within the scope of the appended claim.

What I claim is:

Roll truing mechanism for use with a pair of parallel laterally spaced rolls having end journals and adapted to be rotated comprising a pair of bars adapted to extend between the journals at opposite ends of said rolls and having notched ends for straddling said journals, a track bar secured adjacent the ends thereof to said cross-bars in overlying relation thereto and to extend intermediate the rolls of said pair parallel therewith, a tool carriage mounted on the track bar to slide along the same, a pair of cutting tools on said carriage adapted for engagement with said rolls, respectively, and means operative to slide said carriage, said means comprising a bearing bracket on one end of said track bar, a screw

shaft rotatably mounted in said bracket against endwise movement and threaded through said carriage to extend along the track bar, and a hand wheel on said shaft, said track bar being longer than the length of said rolls between the journals of the rolls to permit the carriage to carry said tools to said ends of said rolls, said notched ends being offset on said bars to dispose the notches in a common plane with said cutting tools where-
by said tools are adapted to cut in the common 10 plane of said rolls.

EDWARD DECHAU.
